UNITED STATES PATENT OFFICE.

SAMUEL D. WASHBURN, OF BOSTON, MASSACHUSETTS, ASSIGNOR OF ONE-HALF TO THE
IN-ER GLOBE LAMP COMPANY, OF BOSTON, MASSACHUSETTS, A CORPORATION OF
MASSACHUSETTS.

INCANDESCENT LAMP.

Specification of Letters Patent. Patented Nov. 14, 1911.

1,008,933.

Application filed January 11, 1908. Serial No. 410,331.

To all whom it may concern:

Be it known that I, SAMUEL D. WASHBURN, a citizen of the United States, and a resident of Boston, in the county of Suffolk and State of Massachusetts, have invented 5 an Improvement in Incandescent Lamps, of which the following description, in connection with the accompanying drawing, is a specification, like letters on the drawing representing like parts.

This invention relates to the shape of the filament part of an electric incandescent lamp to enable the distribution of the light in the most useful direction and at the same 15 time to be such that it can be easily and cheaply manufactured.

It is not claimed that it is broadly novel to change the distribution of the light by changing the shape of the filament, because 20 in Patent No. 654,207, granted July 24, 1900, is shown an early attempt to obtain a shape which would give a downward, or tip distribution of the light. In making the filament shape shown in this patent it was 25 found that the short sharp curves made the filament so fragile that the breakage was excessive, and it was also found that the parts of the filament were so close together that the heat from one part tended to overheat the other parts and thus finally destroy 30 the filament.

In the present invention these difficulties have been overcome and a filament produced in which the parts of the filament do not lie 35 close enough together to produce injurious overheating, and in which the parts are arranged in different planes.

The distribution of light in a downward direction or toward the tip is what is most 40 desired, and the filament of this invention is so shaped as to secure a maximum distribution of the light in such direction.

In this invention the ends of the filament 45 constitute the terminals of connected conical spirals, and thus support the body part of the filament at points very near the centers of gravity, thus giving a rigid as well as a graceful support.

The drawings show the invention in its 50 preferred form applied both to a bulb with and without a reflector.

Figure 1 is a perspective view of a lamp containing one form of the invention where- 55 in the bulb is without a reflector. Fig. 2 is a view similar to Fig. 1 showing a different

form of bulb provided with a reflector. Fig. 3 is a bottom plan view of the filament shown in Figs. 1 and 2.

The shape of the filament of this invention is that of two connected conical spirals, 60 each spiral being exterior of and not overlapping the other. One limb of the filament starting from one leading-in wire is shaped to form one spiral, and the other limb starting from the other leading-in wire is shaped 65 to form the other spiral; the two limbs being continuous the spirals are of course connected at their bases. By this construction the two spirals are supported very nearly 70 from their centers of gravity, thus securing a rigid and graceful support, and the entire 75 length of the filament radiates its light toward the base of the spiral, or the tip of the lamp, thus securing a maximum distribution in that direction.

In the form of the invention illustrated, which is the preferred form, the filament is shaped to form two conical spirals. Considering the entire filament and passing 80 along the filament from one end to the other one of these conical spirals is dextrorsal and the other sinistrorsal. Viewing the filament from the stem end it will be seen that each limb of the filament is formed into a 85 conical spiral and that each one of these spirals is exterior to the other and that in each spiral the filament turns in the direction of the hands of a clock to form its spiral. But it is obvious that it is not essential whether one or both of the spirals turn 90 "clockwise" or "counter clockwise."

In this invention the distance from any part of the filament to its nearest adjacent part is as great as possible because of the varying planes of the spiral, and thus overlapping effects are minimized.

The spirals of this invention may take the form of any mathematical or irregular curve, or be such as would result if formed over a true cone, a distorted cone, or some 100 odd shaped form, so long as they have the essential quality of a spiral, viz., a gradual change in diameter, so that when viewed from the base substantially the entire filament is displayed.

In the drawings the filament is shown as placed in an exhausted bulb with its ends connected to the leading-in wires.

The construction of a lamp is so well known to those skilled in the art of making 110

lamps that any further description of the manufacture of the lamp or the filament is unnecessary.

5 In Fig. 1 the lamp is shown of the common shaped form without a reflector, and in such a shape by means of this invention a very valuable distribution of light can be obtained downward or toward the tip.

10 The more expensive form of lamp provided with a reflector is shown in Fig. 2, and the invention is, of course, equally adaptable to this form, and when combined with a reflector a still more durable distribution of light in a downward direction or toward 15 the tip is secured.

Having described my invention, what I claim as new and desire to secure by Letters Patent, is:

1. An electric incandescent lamp comprising a filament shaped to form two con-

nected conical spirals, each exterior of the other, whereby a maximum distribution of light is secured in a direction perpendicular to the bases of the spirals.

2. An electric incandescent lamp comprising a filament, the limbs of which are each shaped to form a "clockwise" conical spiral, the said spirals being connected at their bases and each being exterior of the other, whereby a maximum distribution of light is secured in a direction perpendicular to the bases of the spirals. 25 30

In testimony whereof, I have signed my name to this specification, in the presence of two subscribing witnesses.

SAMUEL D. WASHBURN.
